UNITED STATES PATENT OFFICE.

THEODORE H. SEXTON, OF GARDEN, MICHIGAN.

ROTARY POTATO-SORTER.

1,169,288.

Specification of Letters Patent. Patented Jan. 25, 1916.

Application filed January 26, 1914. Serial No. 814,495.

To all whom it may concern:

Be it known that I, THEODORE H. SEXTON, a citizen of the United States, residing at Garden, in the county of Delta, State of Michigan, have invented certain new and useful Improvements in Rotary Potato-Sorters; and I do hereby declare the following to be a full, clear, and exact description of the invention, such as will enable others skilled in the art to which it appertains to make and use the same.

This invention relates to potato sorters and has special reference to an improved form of cylindrical potato sorter.

15 The principal object of the invention is to improve and simplify the general construction of devices of this character.

A second object of the invention is to provide, in a device of this character, an improved sorting and cleaning mechanism.

20 A third object of the invention is to provide means whereby the smaller potatoes may be delivered separately from the larger potatoes when no receptacles are used for collecting the same.

A fourth object of the invention is to provide an improved support and drive for the cylinder of such a sorter.

With the above and other objects in view 30 the invention consists in general of certain novel details of construction and combination of parts hereinafter fully described, illustrated in the accompanying drawings, and specifically claimed.

35 In the accompanying drawings, like characters of reference indicate like parts in the several views, and Figure 1 is a side elevation of the machine showing the same tilted into position for digging the potatoes, the 40 elevator being attached. Fig. 2 is a plan view of the machine partly in section, the cylinder being shown in a horizontal position. Fig. 3 is a section on the line 6—6 of Fig. 2. Fig. 4 is a detail view showing a 45 portion of the sorter and certain of the adjacent parts. Fig. 5 is a section on the line 10—10 of Fig. 4. Fig. 6 is a detail view showing the manner of securing certain of the grating bars. Fig. 7 is a detail view 50 showing a portion of the driving mechanism. Fig. 8 is a detail view showing certain clutch mechanism used in connection with the driving mechanism. Fig. 9 is a detail section through a portion of the guide or chute for the small potatoes. Fig. 10 is a partial plan view of the part shown in Fig. 9.

In the present embodiment of the invention there is provided a revolving cylinder consisting of three main parts indicated respectively at 10, 11 and 12.

60 The part 10 consists of a front band 13 and a rear band 14 between which extend the rods 15. In order to secure these rods to the band each of these bands is provided with a pair of spaced rows of openings 16 and each 65 rod has its end downwardly bent as at 17 and passes through an opening of one of the rows. The other row of openings receives the shanks of the eye members 18 which pass over the rods so that the rods are thus secured to each of the bands at two points, the device thus being locked securely in position. It is, of course, to be understood that the rods have their ends riveted to the band by upsetting as are also the shanks of the eye 70 members 18.

75 The portion 11 of the cylinder constitutes the means for sorting out the potatoes beneath a given size and this portion of the cylinder is arranged so that the openings between the bars may be adjusted. Thus it is possible to regulate the size of the potatoes which are sorted out. The band 14 forms 80 the end band for the front end of this device while a band 19 forms the rear band for this portion of the device. Each of the bands 14 and 19 is provided in its edge with a series 85 of recesses 20 wherein are received the pintles 21 of slats 22. These pintles are in alignment near one edge of the respective slat and 90 spaced from the forward pintle is a third 95 pintle 22' which is arranged to enter a respective slot 23 formed in a band 24 which surrounds the band 14 adjacent its edge and is movable thereon. The band 24 is held in adjusted relation on the band 14 by means of a suitable bolt and nut as indicated at 25 and it will be obvious that by loosening this bolt and nut the band 24 may be rotated with reference to the band 14 so that the distance 100 between the slats may be varied and that thereby the sizes of the potatoes which pass out between said slats may be gaged.

105 The rear portion 12 of the revolving cylinder consists of a series of sweeps. These sweeps are indicated at 26 and each comprises a flat plate, preferably of metal, having its edges reinforced by the rods 27 and 28. The band 19 is in the form of a very 110 deep channel so that the rods 28 may be secured to the web of the channel in the same manner in which the rods 15 are secured to

the bands 13 and 14 while the rod 27 may extend through the flange of the channel and have its end riveted thereto by upsetting said end. In this manner the sweeps 26 are arranged radially about the axis of the cylinder. Between the bands 13 and 14 there is also provided a band 29 which is similar in form to the band 19 and has the rods 15 secured thereto by means of eye members 18 in the same manner in which the eye members hold the rods to the bands 14 and 13. Extending around the inside of the cylinder and firmly secured to the bands 13, 14, 19, and 29 are a series of spirally arranged angle irons 30 forming an auger. It is preferred that two or more spirals be used as this is found advantageous in practice. This auger, as the cylinder revolves, carries the potatoes from the front end of said cylinder to the sweeps 26 at the rear thereof, provided the same are of sufficient size, and causes the small potatoes to work up over the cleaning cylinder 10 which separates the dirt therefrom to the sorting cylinder 11 so that these potatoes may drop between the slats of the sorting cylinder. It is to be observed that by reason of the construction of these augers from the angle iron and the spiral arrangement thereof they stiffen the entire structure and make the cylinder very rigid throughout. It is also to be understood, for reasons that will be hereinafter explained, the front portions of the augers are diminished in height and in order to compensate for the diminished height I place at the front of cylinder 10 a series of short auger blades 31, as can clearly be seen by reference to Fig. 2. These short auger blades not only increase and quicken the conveying capacity of the cylinder but also aid in quickly spreading the potatoes and earth as they are delivered to the cylinder and thus greatly facilitate the separation of the earth from the potatoes.

In order to support the cylinder so that it may revolve about its axis I provide the cradles which are indicated in general at 32 and 33. Each of these cradles is provided with flanges 34 which are bolted to the longitudinally extending portions 35 of the main or tilting frame, the front ends of the portion 35 being connected by an integral arch member 36. Each of the cradle members is provided with a longitudinally extending slot 37 and with spaced openings through which extend short shafts 38 carrying rollers 39 which engage against the webs of the respective channels 19 and 29, the flanges of said channels serving to prevent longitudinal displacement of the cylinder with reference to said rollers. For the purpose of oiling the pins or shafts 38 the sides of the cradles are provided with the oil holes 40. Roller bearings 41 are also provided on the sides of the cradle members so as to

eliminate friction between the flanges of the channels and said sides. In order to permit the oil holes and roller bearings being reached by an oil can the sides of the channels are provided with suitable openings 42 which are so arranged that as the cylinder is rotated these openings pass respectively past the openings of the oil holes 40 and pass the bearings 41 thus permitting access to said oil holes and bearings with a properly shaped oil can. It is to be noted that these oil holes or openings 42 are preferably provided with suitable spring covers 43 as can be clearly seen by reference to Fig. 3.

The ends of member 32 have extending outwardly therefrom the stub axles 44 whereon are mounted the ground wheels 44'. It is to be observed that the cradle 32 is so located as to be slightly forward of the center of gravity of the machine so that it may be readily tilted about an axis passing through the centers of the ground wheels. Mounted on the outer ends of the stub axles is a U-shaped frame 45 which is preferably termed the draft frame. Pivoted connected to this frame is a front truck 46 and to the upper end of the front truck is connected the draft tongue 47 while the truck carries the usual clevis 48 for the attachment of draft animals. This front truck 46 is provided with the front wheels 49 and these wheels serve to carry the weight of the forward part of the device and hold the draft frame 45 in fixed angular relation to the surface on which the machine rests. Secured to the draft frame 45 is a quadrant 50 having a suitable opening therein for the reception of the rock shaft 51, the other end of said rock shaft being carried in a bearing 52 secured to said draft frame 45. Extending from the rock shaft 52 is a rock arm 53 which is connected by means of a link 54 with the front of the frame 45. Upon the rock shaft 51 is mounted a latch lever 55 having a handle 56 and being equipped with the usual latch arrangement as indicated at 57 so that the latch lever 55 may be locked in any desired position on the quadrant 50. By means of this arrangement the front of the tilting frame may be raised or lowered as desired and in order to permit of the easy operation of the tilting frame the front arch 36 is made arcuate in side elevation as can be clearly seen by reference to Fig. 1 and upon the draft frame 45 are provided the brackets 58 which carry the rollers 59, the latter bearing against the front arch 36 of the tilting frame 35.

In order to rotate the cylinder of the machine one of the ground wheels 44' has connected to its spokes a series of brackets 60 which serve to support a large beveled gear 61 which meshes with a bevel pinion 62 mounted on a shaft 63 forming part of a bracket 64 secured to the tilting frame 35. 130

This bevel pinion 62 is freely revoluble with reference to the shaft 63 and the end of the bevel pinion is formed with the flat piece 65 having teeth which are adapted to be engaged by clutch teeth 66 fixed upon a pinion 67 which meshes, in turn, with a gear 68 fixed upon the band 14. The gear 67 is furthermore provided with a grooved shipper ring 69 wherein works a collar 70 which 5 is connected by means of a link 71 to a shipper lever 72 provided with a latch 73 working over a quadrant 74 secured to the frame 35 adjacent the bracket 64. On the shaft 63 is fixed a collar 75 and between the collar 10 75 and the grooved member 69 is a spring 76 which normally urges the clutch members 65 and 66 into engagement. 15

Now it will be observed that when the clutch members are disconnected the motion of the machine over the ground will only cause the pinion 62 to revolve idly while if the clutch members 65 and 66 are engaged by proper manipulation of the latch lever the motion of the machine over the ground will cause rotation of the pinion 67 and consequently of the gear 68 which, being connected to the cylinder will rotate the cylinder on its rollers.

For the purpose of delivering the large potatoes to the side of the machine there is provided, beneath the sweeps and in such position as to be worked over by said sweeps, an apron 77 which extends to one side and is there provided with a delivery portion 78 from which the potatoes fall to the ground when the elevator is not in use or, which delivers the potatoes to the boot of the elevator as will be hereinafter explained when the latter is in use.

40 For the purpose of delivering the small potatoes in an even row centrally of the machine there is provided beneath the portion 11 of the cylinder a pair of aprons 79 which are separated beneath the axis of the cylinder by a space 80 so that the small potatoes falling from the separator 11 drop onto one or the other of these aprons and roll down on the same and pass out between the edge of the two aprons.

50 Secured above the cylinder is a conveyer trough 81, the same being connected to the tilting frame by the supplementary frame members 82. These supplementary frame members 82 furthermore serve to support
55 the shaft 83 at the front of the machine and the respective shafts 84 and 85 at the rear of said machine. On each of these shafts there is provided a sprocket 86 and a sprocket conveyer chain 87 extends around
60 these sprockets 86. This sprocket conveyer chain is provided with spaced links 88 having raised portions 88^a whereon are mounted arms 88^b which are normally drawn together by means of a spring
65 88^c. These arms are provided with cam

projections 88^d which, when engaged by the teeth of the sprocket wheel force the arms open. It is to be noted that the lower front sprocket 86 is arranged directly over the shovel so that the arms are opened at 70 this point to grasp the vines and are permitted to close so that the chain moves backward around the rear sprocket and the chain tightening sprocket 88^e the rear sprocket 75 serving the dual purpose of a chain tightener and also to further the freeing of the vines at this point. Thence the chain runs forward over the toothless guide wheel 88^e. Above the cylinder the sprocket chain 87 is provided with a suitable guard 89 to prevent 80 accidental contact with the prongs 88 and injury thereby to the operator. In order to drive the conveyer chain the shaft 85 is furthermore provided with a sprocket 85 90 which is connected by a chain 91 with a sprocket 92 loosely mounted on the remaining axle 44. The hub of the wheel 44' on this axle is provided with clutch teeth 93 which are adapted to engage the clutch 94 formed on the sprocket 92. This sprocket 92 is furthermore provided with a grooved 95 shipper ring 95 wherein works a shipper collar 96 connected by means of a link 97 with a shipper lever 98 provided with the usual latch arrangement 99, the latter working over a quadrant 100 fixed to the top of the cradle 32 on this side of the machine. It will thus be obvious that as the machine passes through the field the sprocket wheel 95 100 92 may be thrown into or out of engagement with the respective wheel 44' and thereby the conveyer chain may be operated or not as desired.

For the purpose of digging the potatoes from the ground the tilting frame has at its forward end a semi-circular band passing under and spaced from the forward end of the frame as indicated at 101. Secured to this band is a shovel 102. Attached to the shovel are the spring arms 101^a which constitute vine guides so that in operation as the chain passes around the sprocket wheel these guides which are tapering springs, set close enough together at their rear ends to guide the smallest vines into an upright position, said guides being furthermore sufficiently flexible to allow the largest bunches of vines to pass between them thus making these members automatically adjustable to all sizes of vines.

The elevator proper consists of a U-shaped chute 104 which is secured to the tilting frame adjacent the lower end of the chute by a bracket 105^a, the bracket being adjustably attached to the tilting frame by means of 125 suitable bolts and nuts. At the front of the machine a brace frame 106^a consisting of side members latticed together as shown is used and the feet of these side members are secured to the tilting frame while the upper 130

end thereof is secured to the chute 104. At the upper end of this chute 104 is a shaft 105 whereon is a roller 106. At the lower end of the chute 104 is a shaft 107 whereon is a suitable roller 108 around the rollers 106 and 108 extends a belt 109 provided with the usual conveyer flights 110 suitably secured thereto. On the shaft 107 is furthermore a sprocket 111 which is connected by 10 means of a sprocket chain 112 to a sprocket 113 carried on a shaft 114 supported in suitable bearings on the conveyer chute and on this shaft 114 there is provided a further sprocket 115 over which the chain 91 passes 15 so that as the chain 91 is moved to operate the potato top conveyer it, at the same time, operates the main conveyer. The chute 104 is furthermore provided with a guide 115^a so that the returning or lower flight of the 20 conveyer will not drag and scrape against the ground wheel on that side of the machine. At the bottom of the conveyer is the usual boot 116 and this boot is provided with an extension 117 so that potatoes delivered 25 from the extension 78 will drop into this extension and thus be delivered to the flights of the conveyer. At the top of the conveyer there is provided a hood 118 and fastened to this hood is a collar 119 which 30 carries a spout 120 in the form of an open trough and this trough is provided with a handle 121 by means of which it can be swung from side to side so that no matter in which direction the machine may be 35 driven about a field the potatoes can be delivered to either side thereof at will. For the purpose of tightening the chain 91 there is provided the usual belt or sprocket chain 40 tightener 122. The machine is preferably provided with a driver's seat 123 which is supported on suitable supports 124 and this seat is so arranged in the usual manner as to be adjustable laterally of the braces thus enabling the 45 device to be used either with the seat arranged centrally, as when the elevator is not attached, or to one side when the elevator is attached. Furthermore the draft frame is provided with suitable brackets 125 to constitute 50 rests for the feet of the driver.

In the operation of the device the same is driven through the field and when the proper point is reached the frame is tilted until the shovel will deliver the dug potatoes into the cylinder. The first part of the cylinder cleans the potatoes, the second part of the cylinder separates the large potatoes 55

from the small potatoes while the space at the end delivers the large potatoes to the side of the machine from whence they are 60 either taken up by the conveyer or deposited in a neat row along side the machine, the small potatoes falling directly in the center of the machine. When the conveyer is used the same may be arranged to deliver to suitable bags, barrels or the like or it may deliver directly into a wagon driven along side of the potato harvester.

There has thus been provided a simple and efficient device of the kind described 70 and of the character specified.

It is obvious that many minor changes may be made in the form and construction of this invention without departing from the material principles thereof. It is not therefore desired to confine the invention to the exact form herein shown and described, but it is wished to include all such as come properly within the scope claimed.

Having thus described the invention, what 80 is claimed as new, is:—

1. In a potato sorting machine, the combination with a pair of spaced circular bands, of slats pivotally mounted in and extending between the same, sweeps secured to and extending outwardly from one of said bands, rods secured to and extending outwardly from the other of said bands, means for supporting said rods and a gear secured to the last mentioned band by means of which both 90 of the said bands may be rotated.

2. In a potato sorting machine, a pair of spaced bands, a plurality of slats of elongated cross section having aligned pintles extending outwardly from the ends thereof 95 adjacent one edge and pivotally mounted in said bands, an additional band circumscribing one of said first mentioned bands and slidable thereon, a pintle on one end of each of said slats adjacent the other edge thereof 100 and pivotally mounted in the last mentioned band, whereby when the said band is moved with relation to the first mentioned band on which it is mounted the slats will be swung about the first mentioned pintles as a pivot 105 and means for securing the slats in their adjusted positions.

In testimony whereof, I affix my signature, in the presence of two witnesses.

THEODORE H. SEXTON.
